CARBON HOLDER

Lester K. Fleischmann, Highland Park, Ill.

Application September 15, 1958, Serial No. 760,975

7 Claims. (Cl. 282—3)

This invention relates to a carbon holder and more particularly to a holder for transfer material to be used with continuous-form stationery strips superposed without carbon interleaved therewith.

In the present invention the carbon holder is mounted upon the stationery itself. The holder maintains transfer sheets in interleaved relation with the stationery in order to make a manifolding assembly. The holder and its transfer sheets may be manually shifted in position along the stationery to position the transfer sheets in register with one set of forms after another.

It is the primary object of this invention to provide a new and improved carbon holder.

Another object is to provide such a holder of a construction to mount upon stationery sheets and to pass around the platen of a writing machine without difficulty. Another object is to provide such a holder which may be easily manufactured and assembled in a novel manner. A further object is to provide such a holder which is not subject to accidental destruction or malfunctioning.

Other objects, features and advantages of the present invention will be apparent from the following description of preferred embodiments illustrated in the accompanying drawings, in which:

Figure 1 is a perspective view of a carbon holder embodying the invention mounted in operative relation with continuous-form stationery;

Figure 2 is a fragmentary sectional view slightly exploded and enlarged taken substantially along line 2—2 in Figure 1;

Figure 3 is a fragmentary sectional view along line 3—3 in Figure 5;

Figure 4 is a fragmentary sectional view along line 4—4 in Figure 5;

Figure 5 is a broken perspective view of a holder removed from the stationery;

Figure 6 is a perspective view of a holder prior to the attachment of carbon sheets thereto;

Figure 7 is a view similar to Figure 5 of slightly different form, and

Figure 8 is a broken perspective view of an assembly embodying a greater number of carbon sheets.

The use of the present carbon holder is with continuous-form stationery such as illustrated in Figure 1. Herein, the stationery S is zig-zag folded along cross lines of weakening in the stationery strips. The thickness of the stationery, the folds therein, and the relative position of one fold to another have all been exaggerated for purposes of clarity of illustration. The uppermost stationery strip 9 has a carbon sheet 10 held in manifolding assembly with the next lower stationery sheet 11 and the same is true for the next two carbon sheets 12 and 14 with respect to the underlying stationery sheets 13 and 15, all illustrated in Figure 1. The carbon sheets in use are of a good grade for repeated use and

2

thus are shifted longitudinally of the stationery strips into register with successive form lengths.

The structure of the carbon holder may best be understood from a description of its method of manufacture.

5 An elongated sheet or strip of paper stock may be prepared with an edge applied film 16 preferably of a tear-proof polyester film. This film will render the paper stock proof against tearing or cutting by the stationery. Thereafter, slots such as 17 and 18 are cut so as to extend 10 across the strip and leave individual blade segments such as 19, 20 and 21. These blade segments or portions extend across the strip in spaced parallel relationship. The slots are generally slightly narrower than the blade segments. It should be understood that Figures 5 through 15 7 show a bar having three blade segments, the bar having been separated from an elongated sheet having many times this many blade segments. It is preferred to use only three blade segments in a bar in order to cut down on the overall width of the carbon holder.

20 After the base of the holder in the form of the bar such as 22 (Figure 6) is prepared, each blade portion is reinforced and stiffened by the application of a flat clock-steel wire 23 positioned over the length and generally the middle of the blade portion. To aid in the

25 placement of the steel reinforcing members, they may be threaded through pairs of openings 24 which temporarily hold the steel wires in place. In Figure 6, two of the blades are shown reinforced by the steel wires, whereas in Figure 7 all three of the bars are so reinforced. The center bar may, in some applications, be sufficiently stiff to avoid the necessity of reinforcement.

30 The strip from which the bars of the holder were cut was preferably provided with a delayed action heat seal adhesive such as is commercially available. This ad-

35hesive may be used to provide an easy and ready assembly of the carbon sheets, blade portions of the holder and reinforcing wires. The bar is assembled so that the rearward edge of a carbon sheet is in alignment with each blade portion. Referring to Figure 3, the carbon sheet 10 has its rearward edge 10' in alignment with the edge of the blade 19. Carbon sheets 12 and 14 are similarly related to blades 20 and 21, respectively. It is preferred that the wire 23 be between the carbon sheet 10 and the blade 19. Once assembled, as illustrated in

40 Figure 3, heat may be applied to render the adhesive active thus making an assembly. The carbon holder is now ready for assembly on continuous-form stationery. The assembly is accomplished as shown in Figure 2.

45 The lowermost stationery strip 15 is laid out flat and the carbon holder placed on top thereof centering the holder laterally of the strip. The next stationery strip 13 is threaded through the slot 17 immediately above the bar 19. This places it in position to be under the next carbon sheet 12. The next stationery sheet 11 is likewise threaded through the slot 18 so as to be under carbon sheet 10. The uppermost stationery sheet 9 is then simply laid over the assembly, completing the manifolding set.

50 Once a set of forms are filled in with the desired writing, the carbon holder and its attached carbon sheets may be manually moved by sliding the holder lengthwise of the stationery. The ends of the bar which integrally join the blade portions form tabs 25. The film 16 covering the tabs may extend beyond the edges of the slots so that the die cut of the slot passes through the film. In this way the stationery will not ordinarily tear or cut the tab, or in any way impair the structure of the holder.

55 When the stationery is fed about a platen the holder passes readily through the pressure rolls. The paper stock of which the holder is made may be only .008" thick and the steel wire may have about the same thick-

ness. The wire is located in the middle of the blade portion, thus making it easier to feed the entire assembly through pressure rolls of a writing machine.

The use of two carbon holders hinged together can provide a manifolding assembly employing up to seven copies.

As illustrated in Figure 8, a lower carbon holder 26 is hingedly joined to an upper holder 27 by a tape-like flat hinge 28 joining the adjacent tab portions 29 and 30. A pressure sensitive tape 31 may join the opposite tabs 32 and 33, once assembled. In use, the two holders are hinged out flat side-by-side; the lower holder is threaded on the lowermost strips of the stationery and thereafter the upper holder 27 is laid over on top of the part assembly already made and the upper stationery strips threaded therein. The pressure sensitive tapes 28 and 31 maintain the two holders 26 and 27 together as a unit and they operate in precisely the same manner as described above. Each of the holders 26 and 27 is provided with carbon sheets C and in essence, consists of one of the carbon holders previously described.

The foregoing detailed description has been given for clearness of understanding only, and no unnecessary limitations should be understood therefrom for some modifications will be obvious to those skilled in the art.

I claim:

1. A carbon holder for use with continuous-form stationery, comprising: an elongated bar of sheet material having at least a pair of spaced blade portions joined integrally at the ends of the bar, said blade portions being separated by cutouts in the bar extending across the major portion of the bar length; an elongated flat metal wire secured to and extending in superposed relation with each blade portion and terminating adjacent the ends of said blade portions; separate sheets of transfer material each having an edge secured to one blade portion providing a plurality of transfer sheets in superposed relation, said cutouts providing spaces for threading continuous strips of stationery between the transfer sheets into manifolding assembly relation, the ends of said bar being spaced to provide exposed tabs at the sides of the manifold assembly and said flat wires and blade portions holding the transfer sheets for unitary sliding movement of the carbon holder lengthwise of continuous strips of stationery.

2. A carbon holder as specified in claim 1 wherein the transfer material sheets are adhesively secured to the blade portions and the metal wire is held captive between the transfer material and blade portion, said wire having a width less than the blade portion and being positioned centrally thereof.

3. A carbon holder as specified in claim 1 wherein the ends of the bar are coated with a tear-proof polyester film and said cutouts extend into an edge of said film to prevent stationery strip from severing the blade portions from the bar.

4. A carbon holder for use with continuous-form stationery, comprising: an elongated bar of relatively lightweight sheet material having longitudinally extending slots forming longitudinally extending blade portions

spaced laterally apart, tab portions at the ends of the bar integrally joining said blade portions; a flat wire stiffener extending over the length of each blade portion and adhesively secured thereto; a plurality of transfer sheets one secured to each blade portion and extending laterally therefrom, said slots providing space for threading stationery strips between the transfer sheets into manifolding assembly, said tab portions providing hand holds for sliding the carbon holder lengthwise of stationery strips threaded in the holder.

5. A carbon holder for use with continuous-form stationery, comprising: an elongated bar of relatively lightweight sheet material having longitudinally extending slots forming longitudinally extending blade portions spaced laterally apart, tab portions at the ends of the bar integrally joining said blade portions, said tab portions having a tear-proof polyester film thereon extending to the ends of said slots; a flat wire stiffener extending over the length of each blade portion and adhesively secured thereto; a plurality of transfer sheets one secured to each blade portion and extending laterally therefrom, said slots providing space for threading stationery strips between the transfer sheets into manifolding assembly, said tab portions extending laterally of a manifold assembly including said transfer sheets for manipulating the holder slidably along stationery strips in said assembly and said film on said tab portions protecting the holder from accidental tearing.

6. A carbon holder as specified in claim 5 wherein a pair of said elongated bars are arranged in superposed relation and means hingedly connect one pair of superposed tab portions for swinging movement of one bar and its transfer sheets into and out of said relation, and means for removably securing the opposite pair of tab portions together to form said manifolding assembly with stationery strips.

7. The method of forming a carbon holder for use with continuous-form stationery, comprising the steps: applying a tear-proof film to lateral edges of an elongated strip of sheet material having a heat seal adhesive coating thereon, die cutting the strip of sheet material laterally thereof to form alternate narrow slots and blade portion extending across the strip leaving integral side bands, temporarily positioning a thin elongated metal wire to extend lengthwise over each blade portion, positioning a plurality of carbon sheets, each with an edge overlaying a blade and said metal wire, then applying heat to adhere said carbon sheets, metal wires and blade portions together, and then severing the margins of said sheet between blade portions to provide a holder with a desired number of carbon sheets thereon.
